UNITED STATES PATENT OFFICE.

ANTONIO CHIARELLI, OF NEW YORK, N. Y.

PROPELLED MECHANISM FOR AIR NAVIGATORS.

Application filed December 11, 1925. Serial No. 74,683.

This invention relates to improvements in the art of aerial navigation, particularly to means which may equally well be used to propel and manœuvre lighter than air and heavier than air crafts, such as dirigibles, balloons, aeroplanes, or the like.

The improvements can also be applied to marine crafts and vehicles to be operated on land.

10 An object of the invention is the provision of novelly situated propellers, and associated controlling mechanism.

15 For further comprehension of the invention, and of the objects and advantages thereof, reference will be had to the following description and accompanying drawing, and to the appended claims in which the various novel features of the invention are more particularly set forth.

20 Fig. 1 is a plan elevation of a substantially cigar-shaped airship constructed according to my invention.

Fig. 2 is a side elevation of the airship shown in Fig. 1.

25 Fig. 3 is a front elevation of the airship shown in Figs. 1 and 2.

Fig. 4 is an enlarged fragmentary side elevational view of the lower part of the airship illustrated in preceding views.

30 Fig. 5 is a vertical sectional view of the rotatable propellers taken on the line 5—5 of Figs. 4 and 7.

Fig. 6 is a fragmentary partly sectional view on the line 6—6 of Fig. 5.

35 Fig. 7 is a partly sectional view taken on the vertical center line of Fig. 5.

Fig. 8 is a top view of the controlling levers situated in the cabin of the ship.

Fig. 9 is a fragmentary sectional view on 40 the line 9—9 of Fig. 8.

Fig. 10 is a fragmentary sectional view on the line 10—10 of Fig. 11.

Fig. 11 is a fragmentary sectional view on the line 11—11 of Fig. 9.

45 Fig. 12 shows a modification of the invention using the propellers on the ends of the ship only.

Fig. 13 shows another modification illustrating the employment of the device on an 50 observation balloon.

Fig. 14 shows a modification illustrating the device employed together with a novelly constructed body.

The body 10 of an airship of suitable material and shape is provided with propellers

11, hereinafter further described, so situated that the planes of rotation of the propellers are different. Referring to Fig. 1, it is readily seen that the propellers located at the front and back are situated on a tangent to these curved parts, while the center propellers align with the body 10, thus providing different planes of rotation. Likewise in Figs. 12 and 13 the propellers are positioned tangential to curved portions of the balloon thereby providing different planes of rotation. This novel way of situating the propellers associated with controlling mechanism is an important improvement over the old methods of allowing propellers to be in the same plane.

The ship, as is usual, has a lower cabin 12, with windows 13, and at one end the controlling chamber 14 in which the controlling mechanism 15, more completely illustrated in Fig. 8, is situated, having controlling wires 16 to the different propellers.

A bottom compartment 17 for the carrying of freight or ballast has support wheels 18 to permit running along the ground, and bumpers 19 with springs 20. For hoisting the member 17 to the cabin 12, ropes 21 engage over drums 22, operated by hand wheels 23, while for detachably securing the member 17 to cabin 12, tongues 24 depending from 17 pass through eyes 25 in the cabin 12, and wedges 26 engage said tongues. Stairways 27 may be provided in said bottom compartment. The propellers 28 are mounted on said cabin in different planes, and are also controlled from 15. These propellers aid in the better operation of the ship. The propellers are driven from shafts 29 connected to the engines of the ship.

The propellers are similar to the one described in a co-pending application, Serial No. 33,645, filed May 29, 1925, but have a novel controlling means. The drum 30 is rotatable on shaft 31 having an eccentric cylindrical portion 32 provided on its external surface with ball bearings 33 rotatably engaging collar 34 having fixed thereto a propeller wing 35 slidably projecting from a slot in the said drum 30. Rigidly fastened to said drum is a gear wheel 36 having a journal 37 and is hollow to provide a journal of shaft 31. The driver gear 38 engages said gear 36, and is connected by shaft 39 to the engines of the ship. The part 40 is only a supporting bracket, and is stationary while

- the adjacent drum is revolved from said gears, and as the drum revolves the propeller wing 35 is pushed around part 32, performing an inward and outward motion. Simultaneous with the inward and outward motion of the wing is another motion, namely, the forward rotating motion of the wing about member 32. It is readily seen that these motions cause a propelling action. The timing of this inward and outward motion may be changed by turning shaft 31 which is accomplished by the controlling mechanism 15, and in this manner the ship is directionally controlled.
- 15 The controlling mechanism 15 consists of a panel 41 having at its ends standards 42, engaging a shaft 43 having a plurality of cone elements 44 thereon, engageable into wheels 45 having control levers 46 each of which is equipped with a pivoted lever 46' to lock the control lever 46 at various angles to a fixed gear segment 46^a, and each of said wheels have attached controlling wires 16 leading to the various propellers throughout the ship and engaged over shafts 31 thereto, and fastened thereto as at 51, whereby turning said wheels the timing of said propellers is changed as before explained. The said wheels may be individually controlled by handles 46, or simultaneously controlled by pressing in lever 47 which is thus held by catch and spring 48; the said cones 44 then engaging the wheels and the pivoted levers 46' are locked to control levers 46 by means of locking rings 46^b which may be swiveled at the top of the said control lever, then turning main wheel 49 co-acts to all wheels. Upon releasing the catch and spring 48 the spring 50 returns the shaft 43 to normal disengaged position.
- 20 The rear end of the body in Fig. 14 shows a corrugated surface 60 with abrupt edges to allow additional lateral surface.
- 25 The operation of the device will be readily understood without further explanation.
- 30 Having thus described my invention, what I claim as new, and desire to secure by Letters Patent, is:—
- 35 1. In a device of the class described, of a panel control board having standards supporting a shaft with a multiple of cones thereon engageable with control wheels having individual control handles, a main control wheel on end of said shaft, a normal position spring, and a catch and spring whereby main control wheel operates said control wheel simultaneously.
  - 40 2. In a device of the class described, of a panel control board having standards supporting a shaft with a multiple of cones thereon engageable with control wheels having individual control handles, wires connected to said control wheels separately engaging adjusting shaft of said propeller blades, a main control wheel on end of said
  - 45 shaft, a normal position spring, and a catch and spring whereby main control wheel operates said control wheel simultaneously.
  - 50 3. In a propelling and manoeuvring system for air crafts, or the like, having a plurality of propellers of the drum and paddle type, each propeller having an adjusting shaft, the combination of a panel control board, a pair of standards depending from said control board, a shaft with a multiple of cone portions thereon supported by said standards, control wheels adjustably mounted on said shaft, and engageable by said cone portions, a control handle depending from each of said control wheels, wires connected to said control wheels separately engaging said adjusting shafts of the drum and paddle propellers, a main control wheel on the end of said shaft having the cone portions, a spring normally urging said cone portions free from said engageable control wheels, and a catch to engage said cone portions and control wheels.
  - 55 4. In a propelling and manoeuvring system for air crafts, or the like, having a plurality of propellers of the drum and paddle type, each propeller having an adjusting shaft, the combination of a panel control board, a pair of standards depending from said control boards, a shaft with a multiple of cone portions thereon supported by said standards, control wheels adjustably mounted on said shaft adjacent said cone portions, and engageable by said cone portions, a control handle depending from each of said control wheels, wires connected to said control wheels separately engaging said adjusting shafts of the drum and paddle propellers, a main control wheel on the end of said shaft having the cone portions, a spring normally urging said cone portions free from said engageable control wheels, and a catch to engage said cone portions and control wheels.
  - 60 5. In a propelling and manoeuvring system for air crafts, or the like, having a plurality of propellers of the drum and paddle type, each propeller having an adjusting shaft, the combination of a panel control board, a pair of standards depending from said control boards, a shaft with a multiple of cone portions thereon supported by said standards, control wheels adjustably mounted on said shaft, and engageable by said cone portions, a control handle depending from each of said control wheels, means to lock said control wheels in adjusted positions, wires connected to said control wheels separately engaging said adjusting shafts of the drum and paddle propellers, a main control wheel on the end of said shaft having the cone portions, a spring normally urging said cone portions free from said engageable control wheels, and a catch to engage said cone portions and control wheels.
  - 65 6. In a propelling and manoeuvring sys-

tem for air crafts, the combination of an inflated airship body, a plurality of propellers of the drum and paddle type spaced therealong with the planes of propeller rotation tangential to the said body and intersecting each other, certain rotatably adjustable shafts connected to each propeller, and adapted to change the timing of the paddle

action, means connected with the shafts for individually adjusting the said shafts, and means connected with the shafts for simultaneously adjusting the shafts.

In testimony whereof I have affixed my signature.

ANTONIO CHIARELLI.
